UNITED STATES PATENT OFFICE.

ALICE KENT TRIMPEY, OF BARABOO, WISCONSIN.

COMBINED SPOOL AND IMPLEMENT HOLDER.

1,165,042.

Specification of Letters Patent. Patented Dec. 21, 1915.

Application filed February 25, 1915. Serial No. 10,480½.

To all whom it may concern:

Be it known that I, ALICE KENT TRIMPEY, a citizen of the United States, residing at the city of Baraboo, in the county of Sauk 5 and State of Wisconsin, have invented a new and useful Combined Spool and Implement Holder to be Used as a Convenience and Labor-Saving Device by All Persons Engaged in Doing Needlework of Any Description, of which the following is the specification.

My invention consists in the novel features hereinafter described, reference being had to the accompanying drawing, in which 15 I have shown one embodiment of my invention, which has been selected by me for purposes of illustration, and the said invention is fully disclosed in the following description and claims.

20 Referring to the drawing: Figure 1 is a perspective view, of my improved spool and implement holder, showing the same attached to a window casing and in use; Fig. 2 is a perspective view of the same showing 25 the holder detached.

The object of my invention is to provide an improved spool and implement holder for use while sewing, and the same is designed to be pivotally attached to supports 30 which are placed in different parts of a room or building.

A further object of my invention is to provide a device of this character which is simple, efficient, and durable in construction, 35 and inexpensive to manufacture.

In the drawing, A represents a suitable support, in this instance a window casing, which is provided with a plurality of screw eyes B, which are adapted to carry my 40 improved spool and implement holder herein-after described.

In practice, it is desirable to place a number of these screw eyes at different points in a room or building, so that the 45 spool and implement holder may be used at different places.

My improved spool and implement holder comprises a bar C provided on its upper surface with a series of vertically rising 50 posts D, which are preferably graduated in height from one end of the bar toward the other. These posts are adapted to act as the supports for spools, one of which is shown at E in Fig. 1. The under side of

the bar C is provided with a plurality of 55 hooks F, which are adapted to support scissors, pincushion, or other similar article.

Rigidly secured to one end of the bar C is a downwardly depending vertical post G which is adapted to be inserted in any set 60 of the screw eyes B before referred to, and swing on the same.

When the device is in use, it is adapted to be swung at an angle to its support A, so that the thread may be pulled from the 65 spools, or the implements supported by the hooks F may be easily reached, and when the device is not in use, it is adapted to be swung parallel with its support A, so that it will not interfere with a person passing the same. 70

It will be apparent to those persons familiar with devices of this character that I have provided a simple and inexpensive structure which may be readily attached and detached, it being understood that changes 75 in the combination and details of the invention may be made within the scope of the appended claims without departing from the spirit of the invention or sacrificing any of its advantages. 80

Having fully described my invention, what I claim and desire to secure by Letters Patent is:

1. In combination with a support provided with a plurality of supporting rings, 85 a vertical post detachably swiveled in said supporting rings, a bar rigidly connected at one end to said post, a series of vertically rising posts provided on the upper surface of said bar adapted to support a series of 90 spools, and a series of hooks provided on the under surface of said bar adapted to support desired implements.

2. In combination with a support having a plurality of supporting rings, a vertical 95 post detachably swiveled in said rings, a bar connected at one end to said post, a series of vertically rising posts provided on the upper surface of said bar adapted to support the spools, said bars being graduated in height from one end of the bar toward the other, and a series of hooks provided on the under surface of said bar adapted to support desired implements. 100

ALICE KENT TRIMPEY.
